UNITED STATES PATENT OFFICE.

ROY W. IDE, OF SPRINGFIELD, ILLINOIS, ASSIGNOR TO IDE PATENTS CORPORATION, OF SPRINGFIELD, ILLINOIS, A CORPORATION OF ILLINOIS.

INTERNAL-COMBUSTION ENGINE.

1,324,824.

Specification of Letters Patent. Patented Dec. 16, 1919.

Application filed February 19, 1917. Serial No. 149,572.

To all whom it may concern:

Be it known that I, Roy W. Ide, citizen of the United States, residing at Springfield, in the county of Sangamon and State of Illinois, have invented a certain new and useful Improvement in Internal-Combustion Engines, of which the following is a full, clear, concise, and exact description.

My invention relates to internal combustion engines and also to an improved interrelation of such engines with carbureters and has a number of objects and advantages in view.

One feature of my invention relates to the admission of air to the carbureter, this admission being regulated by the engine structure. In the preferred embodiment of the invention the engine structure includes a crank case to which the air to be carbureted finds access from the exterior of the engine and from which crank case the air is supplied to the mixing or carbureting chamber of a carbureter. By another feature of the invention this mixing chamber is in the nature of a receptacle that has communication with the intake port of the engine and which is designed to hold liquid fuel to prevent the flow thereof to the crank case. I also provide means, in a four stroke per cycle engine, whereby the admission of the air to the crank case is so proportioned with respect to the nozzle of the carbureter that the air will be admitted to the mixing chamber from the crank case in proper proportion to the liquid fuel that is also admitted to the mixing chamber and whereby the proper degree of partial vacuum will be present in the crank case to cause the flow of liquid fuel from the nozzle in proper amount to the mixing chamber. The partial vacuum in the crank case also promotes the passage of lubricating oil thereto from the bearings that are furnished with lubricating oil from the supply thereof that is provided in the crank case.

I permit some mixture of air and lubricating oil in order that this mixture may enter the intake port of the engine for the purpose of furnishing lubricant to some of the working parts of the engine. To prevent this mixture of lubricating oil and air from becoming too rich I employ baffle plates that prevent the oil that escapes from the bearings from coming into the path of the air

where it enters the crank case and where it leaves the crank case.

The invention has for another object the provision of means for effecting circulation of the liquid fuel in a closed path from and to a source of supply and in excess of the quantity required, the nozzle for directing liquid fuel to the mixing chamber being included in a branch of this path and through which the required amount of fuel is diverted. There is thus afforded a stream of liquid fuel materially in excess of the maximum demand. The invention has for another of its objects the provision of means for discontinuing or obstructing the flow of liquid fuel whereby a less volatile liquid than gasolene may be employed for running the engine and allowing the substitution of a more volatile liquid for starting the engine. The invention also contemplates the employment of a mixing chamber for location adjacent to and in communication with the engine intake port and operating to retain fuel in liquid form to prevent this fuel from being discharged into the crank pit or case of an engine, in a structure where the air to be carbureted is drawn into the crank case and is discharged therefrom into the mixing chamber.

In the preferred form of the invention the passageway through which liquid fuel is taken from the source of supply and is returned thereto is enlarged into a receptacle adjacent the nozzle, this receptacle terminating above the discharge end of the nozzle to afford a head of liquid fuel, during the starting and running of the engine, to assure a proper and sufficient flow of liquid fuel through the nozzle.

There are other characteristics and features of my invention and the invention in all of its characteristics will be fully explained by reference to the accompanying drawings in which Figure 1 is a view in sectional elevation of a four stroke per cycle engine and a carbureter constructed in accordance with my invention; Fig. 2 is a view partially in section and partially in elevation at right angles to the direction in which Fig. 1 is taken and with the piston and other parts in different positions; Fig. 3 is a sectional elevation of the electro-magnetic throttle valve governing mechanism which I prefer to employ; Fig. 4 is a view similar to

Fig. 3 with parts in a different relation; Fig. 5 is a sectional plan view on line 5—5 of Fig. 1; and Fig. 6 is a view on line 6—6 of Fig. 1.

Like parts are indicated by similar characters of reference throughout the different figures.

The engine illustrated, but to the employment of which the invention is not to be limited, is inclusive of an engine shaft 1 that carries the fly wheel not illustrated, and which shaft is provided with a crank structure 3 for turning it. This crank structure is connected with the inner end of a pitman 4 having four strokes per cycle and whose outer end is swingingly connected with a piston 5, all in accordance with well known practice. Most of the features of novelty herein claimed relate particularly to four stroke per cycle engines.

The outer portion 6 of the engine casing is desirably made cylindrical and is co-axial with an inner cylinder 7, spacing 8 intervening between the inner cylinder 7 and the outer cylinder 6 for the reception of engine cooling fluid that may be circulated through said spacing, as will be understood by those skilled in the art. The cylinder 7 has an end wall 9 to constitute such cylinder an explosion cylinder, there being a suitable spark plug (not shown) as will be understood. The working cylinder 13 of the engine receives the piston 5 and, as here shown, functions as a valving cylinder, to which end it is provided with ports 14 and 15 each adapted to serve, first, as an intake port and, second, as an exhaust port, the valving cylinder shown being arranged to operate in a counter clockwise direction as it is viewed from above. Each of the ports 14 and 15 is in turn brought into alignment with the admission or intake port 16 and the exhaust port 17 and inasmuch as there are two ports 14 and 15 in the form of engine shown the valving cylinder is caused to turn a half revolution (during which one or the other of the ports 14 or 15 operates through a complete cycle that embraces the intake, compression, expansion, and exhaust periods) during two revolutions of the engine shaft. The gearing by which the valving cylinder is thus driven at quarter engine speed includes the worm wheel 18 co-axial with and driven by the shaft 1, the worm 19 upon the vertical shaft 20 meshing with the worm wheel 18, the pinion 21 upon the upper end of the shaft 20 and the circular rack 22 carried upon the lower end of the cylinder 13 meshing with the pinion 21. The gas, produced by the carbureter of my invention, is governed in its passage through the admission port 16 by a butterfly valve 23. As set forth in the division of this application Serial No. 175988, filed June 21,

1917, this butterfly valve is fixedly mounted upon a shaft 24 that extends through the carbureter casing wall 25. A pinion 26 is fixed upon the outer end of the shaft 24 and meshes with a vertically reciprocable rack 27 whose upper end is united with the core or armature 28 of a solenoid 28¹. The electro-magnetic responsive device, the solenoid 28¹, is in circuit with the source of current that is regulated by the speed of the engine. This source of current, as illustrated, is in the form of a generator 29 which is driven by the engine, the solenoid responding to the voltage output of the generator. As the voltage decreases in response to the lowered engine speed the valve 23 opens to supply additional gas to the engine to increase the engine speed and vice versa. The range or arc of travel of the throttle valve 23 during starting speed is indicated by the arc 34 in Fig. 3. A throttling or governing range is indicated by the arc 35 in Fig. 4, this arc succeeding the arc 34.

By means to be hereinafter more fully set forth gasoline or other liquid fuel is passed through the bore of the nozzle 36 into a receptacle (constituting a mixing chamber where the air is carbureted) 37 whose receiving space is merged with the intake port 16 and whose walls rise above the bottom of the receptacle for the purpose of trapping the liquid fuel in the composite space afforded by the receiving space of the receptacle and the port 16 during the starting operation of the engine, this fuel being vaporized and carbureted without materially descending into the receptacle as liquid during running speed. The air being carbureted is drawn into the crank case 38 through the pipe or breather 39 and is drawn upwardly through the intake air pipe 40 from which the air finds access to the receptacle 37 and the intake port 16. The passage 40 is one that is apart from the passage afforded by the bore or interior of the cylinder. It will be observed that the air gets into the receptacle 37 through the top opening 40¹ therein whereas hitherto a mere pipe constituted a continuation of the port 16 through the outer end of which air was taken in. With prior arrangements, during starting, the liquid fuel was apt to descend through the pipe 40 into the crank case. By my arrangement the liquid fuel can pass only toward the engine with the result that the mixture is richer during starting. In the embodiment of the invention illustrated the nozzle 36 is stationarily mounted by having threaded connection with the frame portion 41 of the carbureter.

In accordance with another feature of my invention the liquid fuel is pumped by the engine into a receptacle 50 which terminates appreciably above the outlet end of

the nozzle. The engine maintains the fuel in the receptacle 50 above the outlet end of the nozzle 36 so that a head of liquid fuel is maintained in the receptacle 50 to enable the fuel to be properly fed through the nozzle 36. In starting, the moment the engine is turned, this head is established and is maintained whereby the desired rich mixture of gas and air is provided for starting purposes. I have also found that in running there is economy in the consumption of fuel as a result of the head that is maintained in the receptacle 50 above the discharge end of the nozzle 36. The intake channel is enlarged at its outer end to constitute a space in which there is contained a body of felt or other filtering material 51 to clean the liquid fuel, this filtering medium being retained in position by a screen 52. The means by which the engine maintains the liquid at the desired level in the receptacle 50 preferably resides in a gear pump 53 having an intake 54 through which the liquid fuel (contained in the interior 25 of the engine base 55) is drawn by the pump, the pump discharging this fuel through the eduction tube 56 that communicates with the interior of the receptacle 50 at the bottom thereof. The liquid fuel is pumped at 30 a rate faster than the rate at which it is consumed on which account I provide a return passage 57 communicating between the upper end of the receptacle 50 and the interior of the engine base 55. A part of this 35 return passage 57 is established by a pipe 58 through which the pipe 56 passes, there being sufficient clearance between the pipe 56 and the pipe 58 for the return of the liquid from the upper end of the receptacle 40 50. I thus establish a closed path for the circulation of the liquid fuel, a branch or off-shoot of this path including the nozzle through which the required amount of liquid fuel is diverted from said closed path 45 of circulation. The fuel contained in the engine base 55 may be gasolene but I have found that kerosene may be employed as a satisfactory substitute providing the engine is primed or started with gasolene or other 50 more highly volatile air or liquid. When I use one liquid for starting and another liquid for running the engine I provide a valve 59 for sealing the upper end of the pipe 56 during the starting operation. 55 When this valve is seated the more highly volatile liquid may be placed in the receptacle 50 to be supplied to the receptacle 37 in sufficient amount to start the engine. This more highly volatile liquid is desirably placed in the mixing chamber 37 by first locating it in the receptacle 50 through a priming hole 60 which is also a vent hole. When the engine is brought to speed the valve 59 is opened whereafter the engine

will run upon the less volatile liquid. The 65 valve 59 may be regulated in any suitable way. As illustrated it is provided with a valve rod 61 connected at its upper end with a hand lever 62 and surrounded by a spring 63 which is interposed between a collar 64 70 provided upon the valve rod and an abutment 65. When the hand lever 62 is in the position illustrated the spring 63 will close the valve 59 upon its seat but when this hand lever is placed in an upright position, when the engine is at running speed, the rod 61 is raised against the force of the spring and the valve 59 is then unseated. 75

The air to be carbureted is admitted to the crank case through some suitable means that 80 will maintain a desired partial vacuum in the crank case. This means is preferably in the form of a "breather" which is the pipe or riser 39 that is sufficiently elongated properly to choke the passage for the incoming air to secure the desired partial vacuum that is suitably proportioned to the opening or passage through which the gasolene or kerosene finds passage to mixing chamber and which passage may be regulated 85 in any suitable way not forming a specific part of my present invention. This air which is taken into the crank case and is discharged therefrom to the mixing chamber 37 is caused to pass through some of the 90 lubricating oil that falls from the bearings and other parts within the crank case and also through the mist of the lubricating oil within the crank case so that some of this oil will be carried with the air to the mixing chamber and from this mixing chamber 95 will find entrance to the engine through the intake port thereof. Some of the oil that is thus conveyed to the engine with the air that passes to the mixing chamber 37 lubricates 100 the engaging surfaces of the elements 7 and 13. A partial vacuum in the crank case 105 prevents the lubricating oil from following the shafting to the exterior of the crank case, this oil being drawn in, after performing its service, as a consequence of the partial vacuum, as indicated at 66 in Fig. 2. The oil thus drawn back into the crank case finds passage to the bottom of the crank case that holds a supply of lubricating oil, 110 a return passage 67 being illustrated in Fig. 2 for the purpose of permitting such return. The oil is initially supplied to the crank case through the breather 39 which desirably terminates in a funnel 68. A 115 screen 69 is provided in the upper end of the funnel for straining the incoming lubricating oil. In case the screen 69 should become unduly choked I provide an opening 70 in the side of the funnel and beneath the screen 69 that permits the proper flow 120 of oil downwardly into the breather. A plate 71 overlies the opening 70, without 125

1
closing it, and prevents the oil that is passed through the funnel from passing through the openings 70. The lubricating oil is desirably forced into the bearings to which 5 end I employ a pump desirably in the form of a gear pump 72. This pump draws lubricating oil through the passage or pipe 73 and forces it through the passages 74 to the various bearings to be lubricated. The 10 discharge end of the passage 73 is materially below the upper level of the body of lubricating oil in the crank pit, this body of lubricating oil modifying the sucking action of the vacuum upon the oil in the 15 passage 73 in a suitable manner. The lubricating oil, being forced under pressure to the bearings, finds exit therefrom in subdivided form as indicated at 75. It is desired to prevent too rich a mixture of the 20 air (which is on its way to the mixing chamber) and lubricating oil, to which end I provide a baffle plate 76 adjacent the exit pipe 40 and which serves virtually to form a lower continuation of said exit pipe to 25 cause the air to enter the same at a place below some of the points of escape 75 of some of the oil. This plate 76 extends from side to side of the engine crank case (Fig. 2) so as to widen the inner end of the outgoing 30 pipe to reduce the velocity of the air where it enters the pipe and thereby reduce the extent of the mixture of the air and lubricating oil where the air enters the outgoing pipe. I also provide another 35 baffle plate 77 that virtually constitutes a flaring continuation of the pipe 39 and prevents the lubricating oil from being dashed into the cylindrical portion of the pipe 39. The base of the engine 55 that holds the 40 kerosene or other liquid fuel is separated from the crank pit by the bottom wall 78 of the crank pit so that the lubricating oil chamber and the kerosene chamber are not in communication. The sleeve or elongated boss 79 projects upwardly from the base wall 78 and terminates above the highest level of the lubricating oil. The shaft 45 20 that drives the fuel pump 53 passes

through the sleeve 79 which serves to maintain the separation of the chambers which 50 hold the lubricating oil and kerosene.

To enrich the mixture in starting the engine, the breather 39 may be partially closed (as by means of the spring valve 80) to increase the vacuum in the crank case to increase the flow of liquid fuel through the nozzle 36.

While I have herein shown and particularly described the preferred embodiment of my invention, I do not wish to be limited to the precise details of construction shown as changes may readily be made without departing from the spirit of my invention, but having thus described my invention I claim as new and desire to secure by 65 Letters Patent the following:—

1. An internal combustion engine including a cylinder having a port for the admission of engine operating gas to the engine; an engine piston reciprocating in the cylinder; a mixing chamber in communication with said port; a nozzle for conveying liquid fuel to said mixing chamber; a source of liquid fuel; engine controlled means for supplying liquid fuel from said source to 75 such nozzle; and a valve for obstructing the flow of such liquid to the mixing chamber to permit of the admission of other liquid fuel to said chamber for priming.

2. The combination with an internal combustion engine; of a carbureter, the casing of the engine having separated lubricant and liquid fuel containing chambers, the latter chamber being below the former; a pump for effecting the flow of the liquid 85 fuel to the carbureter and having an engine operated pump operating shaft that extends into the fuel containing chamber; and a sleeve for maintaining separation between said chambers and passing upwardly 90 into the lubricant containing chamber and through which sleeve said shaft passes.

In witness whereof, I hereunto subscribe my name this 30th day of December A. D. 1916.

ROY W. IDE.
